STOP FOR THE OPERATING BAR OF DOOR
FASTENERS

George E. Dath, Mokena, Ill., assignor to W. H. Miner, Inc., Chicago, Ill., a corporation of Delaware

Application November 30, 1945, Serial No. 631,904

5 Claims. (Cl. 292—218)

1

This invention relates to improvements in a stop for the operating bar of door fasteners.

One object of the invention is to provide a door fastener for hinged doors comprising a rotary operating bar mounted on the door and having keeper engaging crank members at opposite ends thereof cooperating with fixed keepers, operated by a lever on the bar, wherein stop means is provided for arresting rotation of the bar and holding the lever spaced from the door when the latter has been forced open and thus prevent marring of the door which would otherwise occur if the operating handle were permitted to contact the same.

A more specific object of the invention is to provide a door fastener mechanism as set forth in the preceding paragraph, wherein a bearing or guide bracket is provided on the door for rotatably supporting the bar, and the stop means comprises a one piece bearing block on the bar having bearing portions at opposite ends rotatably journaled in cooperating seats in the bracket, and a radially extending stop projection between its ends having shouldered engagement with a cooperating stop on the bracket to arrest rotation of the bar and hold the operating lever spaced from the outer side of the door when the latter has been forced open.

Other objects of the invention will more clearly appear from the description and claims herein-after following.

In the drawings forming a part of this specification, Figure 1 is a broken, front elevational view of a wall provided with a door opening, and a pair of hinged doors for closing said opening illustrating my improvements in connection therewith. Figure 2 is a front elevational view, on an enlarged scale, of the mechanism at the mid portion of the bar, as shown in Figure 1, the upper and lower end portions of the bar being broken away. Figure 3 is a horizontal sectional view, corresponding substantially to the line 3—3 of Figure 2, the bearing block being shown in plan. Figure 4 is a transverse, horizontal sectional view through the bearing block of my improved mechanism, taken at approximately the mid portion of said block. Figure 5 is a detailed perspective view of the bearing block. Figure 6 is a vertical sectional view, corresponding substantially to the line 6—6 of Figure 2. Figure 7 is a top plan view of the bearing bracket for supporting the bar. Figure 8 is a view similar to Figure 3, showing the parts in different position, the bar being shown in the position it occupies when the door has been forced open and rota-

2

tion of the bar has been arrested by the stop means.

In said drawings, 10 designates the side wall of a refrigerator car having a door opening 11 therein, which is closed by a pair of hinged doors 12 and 13. Each door is provided with the usual sets of hinges 14—14 along the vertical outer edges thereof, by which the door is swingingly supported. The door 12, which is that first closed, 10 and the door 13 have meeting edges which are beveled and so inclined that the door 13 will maintain the door 12 in closed position and wedge the same shut when the door operating mechanism is actuated. The edges of the doors 15 and the cooperating edges of the door frame are provided with the usual insulating packing material, not shown.

My improved door fastener mechanism comprises broadly a rotary bar A; a pair of keeper 20 engaging end members or castings B—B; an operating handle lever C; top and bottom guide brackets D—D; a pair of keepers E—E with which the end castings cooperate; an intermediate guide or bearing bracket F having stop means 25 thereon; and a bearing block G carried by the bar and having a stop projection or shoulder cooperating with the shoulder of the bracket F.

The bar A is of substantially rectangular cross section and has the end castings B—B secured 30 thereto.

The castings B—B which are at the upper and lower ends of the bar respectively are of similar 35 design, but reversely arranged. Each end casting B is of well-known design, comprising a forked portion embracing the flat bar A at opposite sides and riveted thereto, and a crank member at the outer end thereof cooperating 40 with the corresponding keeper E. The bar A is rotatably supported by the keeper engaging end members B—B which are journaled in the brackets D—D in the usual manner.

As clearly shown in Figure 1 of the drawings, the operating bar A is vertically disposed and has the crank portions thereof projecting above 45 and below the door to engage the keepers E—E to force the door shut when the bar is rotated in one direction and force the door open when the bar is rotated in the reverse direction. The bar A is rotated by means of the operating 50 handle lever C, which is pivotally secured to the bar so that it may be dropped to vertical position.

Intermediate its top and bottom ends, the bar A is supported and guided by the bracket F, which 55 is secured to the door 13. The guide bracket F is

in the form of a U-shaped strap 15 having laterally projecting ears or securing lugs 16-16 by which the bracket is mounted. The curved U-shaped strap portion 15 accommodates the bearing block G for rotary movement. As will be seen upon reference to Figures 3, 7, and 8, the bearing bracket F is open at the rear side, as indicated at 17, said opening being of such a width as to permit insertion of the bearing block G into the bracket in lateral direction.

At the top and bottom thereof, the bracket F is provided with interior bearing seats 18-18 which communicate with the opening 17, these seats being of circular outline and rotatably accommodating the upper and lower end portions of the bearing block G. As shown most clearly in Figures 3 and 8, the circular walls of the seats 18-18 merge with the side walls 19-19 of the opening 17. Between its top and bottom ends, the body of the strap portion 15 of the bracket F is enlarged or expanded, as indicated at 20 in Figures 2 and 3, said enlarged or expanded portion presenting an interior seat or bore 21 of greater diameter than the seats 18-18. The seat 21 forms a guideway for the stop projection of the bearing block G, as hereinafter pointed out, and presents a circular side wall 22 concentric with the circular side walls of the seats 18-18. The circular side wall 22 of the seat or bore 21 merges with the side wall of the opening 17 at the left hand side of the bracket F, as seen in Figures 3 and 8. At the right hand side of the bracket F, as seen in Figures 3 and 8, the seat 21 terminates in a transverse stop shoulder or wall 33 formed on a projecting portion 24 at the back of said bracket, which portion extends into the opening 17. The opening 17 is thus contracted or of lesser width at the bearing seat 21 than at the bearing seats 18-18.

The bearing block G is vertically slotted, as indicated at 25, to accommodate the bar A, which the block embraces. The slot 25 is open at the rear or right hand side of the block, as seen in Figures 3, 4, and 8, and as shown in the perspective view, Figure 5. The block G includes top and bottom, disc-like bearing portions 26-26 through which the slot 25 extends, and a radially projecting arm 27 midway between its top and bottom ends. The arm 27 protrudes outwardly beyond the disc portions 26-26, as clearly seen in Figures 3, 5, and 8. The arm 27 is spaced from the top and bottom disc portions 26-26, being midway between the same, and is laterally enlarged at its outer end, thereby providing a head portion. The head portion has flat side faces 28 and 29 and a rounded end face or edge 30. The side face 28 forms a stop shoulder adapted to cooperate with the shoulder 23 of the bracket F, as hereinafter pointed out.

The disc portions 26-26 of the block G are of such a diameter that they have a rotary bearing fit within the seats 18-18 and will pass freely, in edgewise direction, through the opening 17 to permit engaging the same within the bearing seats of the bracket F, and the arm 27 is of such a width as to pass freely in endwise direction through the contracted portion of the opening 17. The length of the arm 27 is such that it rotatably fits within the bearing seat or guideway 21 of the bracket F. The stop wall or shoulder 23 of the bearing bracket F and the arm 27 of the block G are located so that rotation of the bar A will be stopped by engagement of the arm 27 with the shoulder 23 when the lever C is swung from the position shown in Figure 1 to a position adjacent

to the door 13 but spaced from the face of the door, thereby providing substantial clearance between the operating handle lever and the door.

In assembling the parts of the mechanism, either the bearing block G may be first placed on the bar A and the bracket F engaged over the block or the block G may be first assembled with the bracket and then engaged over the bar. In either case, in engaging the bearing bracket F over the block G, the block is placed so that the arm 27 is in lengthwise alignment with the opening 17 at the rear of the bracket F, that is, it is turned or rotated through an angle of 90° in contra-clockwise direction from the position shown in Figure 3, so that the arm will pass freely through said opening. The bracket F is then secured to the door, thus supporting the bar for rotary movement. As will be evident, endwise disengagement of the block G from the bracket F is positively prevented by means of the arm 27 of the block which is engaged in the guideway or seat 21 of the bracket.

In Figure 1, the doors are shown in locked and closed position, the keeper engaging crank portions of the operating bar A being in engagement with the keepers and the operating handle lever C locked against rotation by the latch means 31, as is well known in this art. To open the doors, the operating handle lever C is unlatched and swung from the position shown in Figure 1 to the right and inwardly toward the door 13, thereby rotating the bar A and through the camming action of the crank members forcing the door open. The lever C is positively arrested before the same reaches the position where it would engage the door 13 by the stop shoulder 23 of the bracket F being engaged by the arm 27 of the bearing block G, as shown in Figure 8. The operating handle lever is thus held clear of the door and marring of the finished surface of the latter is positively prevented as the handle is swung on its pivotal connection with the bar to drop to vertical position alongside the latter. This stop means also performs in the manner of a safety device, preventing the attendant from injuring his hand which might otherwise occur by the same being caught between the handle portion of the lever and the door.

I claim:

1. In a door fastener for hinged doors, the combination with a rotary operating bar having keeper engaging means thereon cooperating with fixed keepers; of a bearing block embracing the bar and rotatable therewith; a supporting guide bracket fixed to the door in which the block is rotatably supported; a stop shoulder interiorly of said bracket; and a stop projection on said block engageable with said shoulder for arresting rotary movement of the bar, the portion of said block carrying the stop projection being enclosed by said bracket.
2. In a door fastener for hinged doors, the combination with a rotary operating bar having keeper engaging means thereon cooperating with fixed keeper means; of a bearing block embracing the bar and rotatable therewith; a supporting guide bracket fixed to the door in which the top and bottom end portions of said block are rotatably supported; a radial stop projection on said block between the top and bottom ends thereof; and an interior stop shoulder on said bracket in the path of rotary movement of said radial stop projection and engageable thereby to arrest rotary movement of said bar.
3. In a door fastener for hinged doors, the

combination with a rotary operating bar having keeper engaging means thereon cooperating with fixed keeper means; of a supporting guide bracket fixed to the door, said bracket having top and bottom, interior bearing seats and a guideway intermediate said seats; a bearing block embracing said bar and rotatable therewith, said block having bearing portions at the upper and lower ends rotatably engaged in said top and bottom bearing seats; a radially projecting arm on said block between said bearing portions, said arm being rotatably guided in said guideway; and a stop shoulder in said guideway in the path of rotary movement of said arm and engageable thereby to arrest rotary movement of said bar.

4. In a door fastener for hinged doors, the combination with a rotary operating bar having keeper engaging means thereon cooperating with fixed keeper means; of a bearing block embracing said bar and rotatable therewith, said block having cylindrical bearing portions at the upper and lower ends thereof and a radially projecting arm intermediate said bearing portions; a supporting guide bracket secured to the door, said bracket having top and bottom bearing seats within which said bearing portions of the block are rotatably journaled, said bracket having an interior guideway between the top and bottom ends thereof within which said arm is guided for rotary movement; and a stop shoulder on said bracket within said guideway in the path of rotary movement of said arm for arresting rotary movement of said bar, said guide bracket having an opening at the rear thereof communicating with said seats and guideway, said opening being of a size to permit lateral insertion of the block within said bracket with said arm, aligned lengthwise with said opening.

5. In a door fastener for hinged doors, the

combination with a rotary operating bar having keeper engaging means thereon cooperating with fixed keeper means; of a bearing block embracing said bar and rotatable therewith, said block having cylindrical bearing portions at the upper and lower ends thereof and a radially projecting arm intermediate said bearing portions; a supporting guide bracket secured to the door, said bracket having top and bottom bearing seats within which said bearing portions of the block are rotatably journaled, said bracket having an interior guideway between the top and bottom ends thereof within which said arm is guided for rotary movement; and a stop shoulder on said bracket within said guideway in the path of rotary movement of said arm for arresting rotary movement of said bar, said guide bracket having an opening at the rear thereof communicating with said seats and guideway, said opening being of a size to permit lateral insertion of the block within said bracket with said arm, aligned lengthwise with said opening.
